UNITED STATES PATENT OFFICE.

GEORGE A. SMITH, OF PAULDING, OHIO, ASSIGNOR OF THREE-FOURTHS TO
CHARLES E. LOTT, CHARLES S. JACKSON, AND RALPH D. WEBSTER, OF
SAME PLACE.

PUMP.

SPECIFICATION forming part of Letters Patent No. 450,535, dated April 14, 1891.

Application filed November 13, 1890. Serial No. 371,349. (No model.)

To all whom it may concern:

Be it known that I, GEORGE A. SMITH, a citizen of the United States of America, residing at Paulding, in the county of Paulding and 5 State of Ohio, have invented certain new and useful Improvements in Pumps; and I do hereby declare the following to be a full, clear, and exact description of the invention, such as will enable others skilled in the art to which 10 it appertains to make and use the same, reference being had to the accompanying drawing, and to letters of reference marked thereon, which form a part of this specification.

This invention relates to improvements in 15 force-pumps.

The object of the invention is to provide a pump which is simple and effective in operation, and when operated will give a continuous flow of water from the pump-spout; and 20 it consists in a pump in which the piston-rod and pump-stock are alternately raised and lowered, said parts being connected to a common lever, the device acting both as a suction and lift pump.

25 In the accompanying drawing, forming part of this specification, the figure is a side view, partly in section.

A refers to the platform above the well or cistern, to which is rigidly secured a standard 30 B, acting as a fulcrum for a lever C. To the end of this lever the pump-stock or vertical pipe D is connected in any suitable manner, and upon the other side of its fulcrum is pivoted the piston-rod. The distance between 35 the fulcrum and points of connection of the pump-stock and piston-rod may be varied according to the diameter of the stock or pipe and cylinder in which the piston works. The piston rod and pipe D pass through suitable 40 guides attached to the platform A, and the end of the lever is preferably connected to the pump stock or pipe D by means of a slotted band d, clamped thereon by a bolt, as shown. The lever, near its free end, carries 45 an adjustable weight W, which acts as a counterpoise or balance for the weight of the pipe D.

To the lower end of the pipe D is connected a T-coupling F, to the lower end of which is 50 secured a short section G, preferably rectangular in cross-section, which contains a horizontal valve-seat g, to which is pivoted the

valve g'. Below the valve-seat g the section G has an opening G', over which plays a valve g², opening inward. The section G is connected by a curved pipe H to the cylinder I, in which plays the piston e. This cylinder is also rectangular in cross-section, though it is obvious it may be cylindrical without departing from my invention. The cylinder I above 55 the limit of the upward stroke of the piston is provided with an opening I', covered by a valve i, which opens inward. The upper end of the cylinder is closed by a suitable plug and packing, through which the piston-rod 60 plays. The cylinder I has a horizontal offset with flanges, to which is connected a section K, carrying a valve k, this section being also connected to the T-coupling F by a union or otherwise. 65

The lever C adjacent to its fulcrum is provided with projections or lugs which are adapted to abut against the standard to limit the oscillation of said lever, and when the lever is not provided with such projections 70 bands are attached to the pipe D above and below the platform to abut against the same and answer the same purpose.

The parts G, K, and I are, as heretofore stated, preferably made rectangular in cross-section, the object of such construction being to provide larger openings and valves than could be properly used were they cylindrical and of the same diameter. 80

In practice I prefer to have the lower portion of the pump submerged, and when the lever is reciprocated the water will enter through the ports G' and I', and a few strokes will fill the pump-stock D. On the upstroke of the piston-rod the other parts of the pump 85 will descend, and the water above the piston will be forced out of the exit-opening of the pipe. On the reverse stroke of the lever the pipe D and parts connected thereto will be raised and the piston lowered, which forces 90 the water previously drawn into the connection H by the upstroke of the piston above the valve g' and out of the exit-opening in the pipe D, thus giving a constant and unbroken stream of water as long as the lever 95 is operated. It will be noted that the water is forced as the parts are reciprocated, and that the valves are so positioned that the spaces above and below the piston are being 100

filled while the opposite face of said piston is forcing the water. As the lever operates the piston-rod and rigid parts of the pump connected to the pipe D in opposite directions—that is to say, while the pipe D is moving up the piston-rod is moving downward—the length of the stroke of the lever is reduced one-half and the pump rendered doubly effective.

- 10 I am aware that prior to my invention it has been proposed to vertically reciprocate the pump-tube and cylinder having a stationary piston-rod, and I do not claim such construction as my invention, for it is obvious 15 that if the piston-rod in my present invention was held immovable the effectiveness of the pump would be reduced more than one-half, and it would require more power to operate the same, the parts not serving to counterbalance each other.

Having thus described my invention, what I claim as new, and desire to secure by Letters Patent, is —

1. The combination, in a pump, of a vertically-movable discharge-pipe carrying and 25 having rigidly attached thereto valve-connec-

tions G and K, which communicate with a cylinder, the cylinder and connection G, having valved openings G' and I', a piston-rod connected on one side of the fulcrum of an operating-lever and the discharge-pipe on the other, substantially as set forth.

2. The combination, in a pump, of a cylinder having a closed upper end, a valved opening above the limit of the upward movement of said piston, a valved tube connecting the upper portion of the cylinder with the discharge-pipe, a connection or box G, having a valve g' and a valve-opening G', and a pipe connecting the lower end of the cylinder with the connection G, the pipe D, to which the aforesaid parts are rigidly connected, being connected to the piston-rod E, so that the parts will be alternately reciprocated, substantially as set forth.

In testimony whereof I affix my signature in presence of two witnesses.

GEORGE A. SMITH.
